BRANDTJEN AND KLUGE, INC., OF ST. PAUL, MINNESOTA, A CORPORATION OF
MINNESOTA.

SHEET-FEEDING DEVICE.

Application filed May 7, 1923. Serial No. 637,139.

Our invention relates to improvements in sheet feeding devices, of the character illustrated and described in our co-pending application for Letters Patent of the United States for pneumatic feeding devices for printing presses, filed July 19, 1919, Serial Number 311,992, now matured into Patent No. 1,472,656 of October 30, 1923.

Our efforts to meet the growing need for dependable automatic sheet feeders, especially for printing presses, have led to the development of the present invention, an object thereof being to embody in devices of this nature those needed improvements bringing about low cost of manufacture, accuracy, dependability and longevity in use and, particularly, ease of adjustment to effect desired and uniformly true operations. Another object of this invention is to provide in a pneumatic sheet handling mechanism, simple and effective suction interrupting means capable of ready adjustment to attain precise control over the handling of sheets of various stocks at different speeds.

A further object is to supply suction controlling means for pneumatic sheet handling devices, the same permitting of the positive taking of sheets of different stocks and the uniformly accurate delivery thereof at selected positions, during various speeds and with suction creating means of relatively small capacity.

With the foregoing and other objects in view, which will appear in the following description, the invention resides in the novel combination and arrangement of parts and in the details of construction hereinafter described and claimed.

In the drawings, Fig. 1 illustrates a job press, in elevation, and a device for feeding sheets applied thereto and embodying our invention; Fig. 2 is a perspective view, in detail, illustrating a portion of said device; Fig. 3 is a detail view showing, in plan, the structure illustrated in Fig. 3; Fig. 4 is a vertical, central sectional view taken as on the line 4-4 of Fig. 3; Fig. 5 is a similar view taken as on the line 5-5 of Fig. 3; Fig. 6 is a transverse sectional view, taken on the line 6-6 of Fig. 4; Figs. 7 and 8 are vertical sectional views taken as on the line x-x of Fig. 3 and showing different positions of the valve actuating mechanism.

Referring to the accompanying drawings,

it will be seen that a tubular standard 10, 55 secured in brackets 11 and 12 on the side of a press A, carries an elevated head piece B, consisting of a bearing 13 and a tubular housing 14 cast integrally and at right angles with respect to each other. The lower end 60 of the housing 14 is fitted over the upper end of the standard 10. Said housing 14 is kerfed longitudinally as at 15 and formed with ears 16 thereon through which a clamping bolt 17 projects, said bolt serving 65 to grip the housing 14 upon the standard 10 and thereby firmly secure the head piece B in place. Mounted to rock, in the bearing 13, which rests horizontally above the press, is an eccentric bushing 18. This bushing 70 has an enlargement in the form of a disc 19 at the outer end thereof and an axially offset extension 20 at its inner end. A bore 21 reaching through the bushing 18 and through said extension 20 and enlargement 75 19, receives a rock-shaft. A rocker arm 23 keyed on the outer end of the rock-shaft 22 and operated through a rod 24 turns the shaft 22 and oscillates a feeder arm 25 secured to the inner end of said shaft. A connecting rod 26 attached to the disc 19 is operated, like the rod 24, in time with the press and through suitable means such as that disclosed in our co-pending application hereinbefore referred to. While the rocking of 80 the bushing 18 by the rod 26 causes the extension and retraction of the feeder arm 25, as particularly set out in said co-pending application, the prime function of such movement in so far as this application is 85 concerned, resides in the attendant rocking of the disc 19 upon which is mounted a latch trip-pin 27 to be more fully hereinafter explained.

The feeder arm 25 is hollow through the 95 greater part of its reach and carries a suction grip 28 at the free end thereof. A tube 29 connects said suction grip 28 with the hollow feeder arm 25, and said arm is connected through a flexible tube 30 with the 100 housing 14. Said housing, in turn, communicates with the bore of the standard 10, which communicates with a suction pump (not shown) or other air exhausting means through a tube 31 and vacuum relief fitting C joining 105 said tube with said standard. Dual valve mechanism is supplied to obstruct and clear the passageway or conduit between the pump

and suction grip 28 so that in the rapid oscillation of the feeder arm 25, sheets will be firmly grasped at receiving position, taken from the magazine 32 without slipping 5 page on the grip and uniformly released at various selected points in the sweep of the arm 25, whereby desired ultimate positions of rest of said sheets on the press platen are accurately attained. A valve cage (Figs. 4 and 5) comprising a cylindrical body 33, formed with a head 34 and having a detachable cap 35 on said head, is applied to the housing 14, the body 33 being snugly fitted in the upper end of said housing and secured in place by means of anchoring screws 36 reaching through the head 34 and threaded in the wall of the housing. A central bore 37, extending upward from the bottom of the body 33, terminates short of the head 34. A ball valve 38 guided in said bore 37 has a seat 39 in an apertured plug 40 fitted in the upper end of the standard 10. An expansion spring 41 in the bore 37, supplementing the action of gravity and suction, 10 yieldingly seats said ball valve 38. A valve lifter D includes a stem 42 journaled vertically in the body 33 of the valve cage, and a trip arm 43 formed by bending the lower end of said stem into horizontal relation and beveling the same to supply a ball lifting surface 44. A segment in the wall of the body 33 is cut away as at 45 to permit of the swinging of said arm 43 and by-passes 46 are machined in said body 33 in communication with the bore 37 to lend ample capacity to the passageway around the ball valve 38 above its seat 39. A port 47 in the body 33 registers with the open end of a nipple 48 threaded in the housing 14 and to which 15 the tube 30 to the feeder arm 25 is connected. A duct 48 leading upward from the bore 37 in the body 33 opens to the outer air at the top of the head 34. A seat 49 is formed at the mouth of this duct for a second ball valve 50 guided in the cap 35 and yieldingly seated by means of an expansion spring 51 confined in said cap. In addition to the stem 42, the valve lifter D includes a lever d secured between its inner and outer arms 53 and 54 to the upper portion of said stem 42. A screw 55 threaded horizontally through the inner arm 53 of the lever d has a notched finger piece 56 thereon, which is yieldingly held against rotation by means of a bar 55 secured to a lug 58 on the arm 54 of the lever d. This screw 55 is arranged so that the pointed end 55^a thereof will pass through an opening 35^a in the cap 35 and lift the ball valve 50 upon the swinging of 20 the lever d. A latch bar 59 pivoted on the bearing 13 is yieldingly depressed against a stop surface 59^a on said bearing by means of an expansion spring 60 encircling a guide screw 61 and interposed between the head 61^a of said screw and the upper side of said 25 bar 59. The forward tip of the bar 59 supplies an abutment 62 to hold the lever d in one position (Figs. 3 and 8) against the action of a tension spring 63, and a lug 64 underneath said bar provides a stop for limiting the retraction of said lever by the action of said spring 63 (Figs. 2 and 7). An arm 65 swung on the shaft 22 between the rocker-arm 23 and disc 19 is formed with a cam 66 at its free end to engage the rearwardly turned lug 54^a on the outer arm 54 of the lever d and swing said lever. A link 67 joining the rocker-arm 23 and arm 65 is pivoted at one end to the former and supplied with a slot 68 at the other end thereof. A binding screw 69, threaded in a boss 70 on the arm 65, reaches through said slot 68 and binds the link 67 against said boss 70. The slot 68 permits of various angular adjustments of the arm 65 with respect to the rocker-arm 23, whereby the lever d will be engaged and swung by the cam 66, earlier or later, through greater or less distances in the latter part of the feeding sweep of the feeder arm 25.

The swinging of the lever d by the cam 66 to position (Figs. 3 and 8) permitting of the depression of the latch bar 59 results in the seating of the lower ball valve 38. The upper ball valve 50 is unseated simultaneously with the seating of said lower ball valve 38, or before, or after, according to the adjustment of the screw 55. The seating of the lower ball valve 38 seals the upper end of the standard 10, which serves as an exhaustion chamber during the completion of the delivering swing of the feeder arm 25 and the return thereof to sheet receiving position. The unseating of the upper ball valve 50, admits outer air to the suction passageway, the effect thereof, with or after the seating of the lower ball valve 38, resulting in the destruction of the vacuum between the grip 28 and said valve 38 and the consequent more or less delayed releasing of a sheet by said grips. Unseating the upper ball valve 50 prior to the seating of the lower ball valve 38 reduces the vacuum at the grip 28 and prepares for the substantially instant release of a sheet therefrom when suction is ultimately cut off by the seating of said lower ball valve 38. Operating to obstruct the bore of the standard 10, during the return swing of the feeder arm 25 and during varied limited times 105 thereafter, the lower ball valve 38 is unseated as the feeder arm 25 reaches sheet receiving position. This unseating of said lower ball valve 38 is caused by the action of the spring 63 on the lever d following the elevation of the latch-bar 59 (Figs. 2 and 7) by the trip-pin 27 on the disc 19. When the screw 55 is set to unseat the upper ball valve 50 simultaneously with or before the seating of the lower ball valve 38, said upper 110 115 120 125 130

valve 50 is released and permitted to close upon its seat at the time of the unseating of the lower valve 38. When said screw 55 is set to unseat the upper valve 50 after the seating of the lower valve 38, it will be understood that said upper valve 50 is permitted to seat as soon as the cam 66 is withdrawn sufficiently to permit the return of the lever *d* by the action of the spring 63 to position (Figs. 3 and 8) against the abutment 62 on the latch bar 59.

In Fig. 7, the dotted line 25^a illustrates diagrammatically the position of the feeder arm 25 at the time of the taking of a sheet from the magazine 32. Just prior to the elevation of said arm 25 into this position, the trip-pin 27 on the disc 19 lifts the latch bar 59, thus restoring suction at the mouth of the grip 28. This time for the resumption of suction at the grip 28 is fixed, but the time for discontinuing suction at said grip for releasing sheets on the platen varies in the sheet carrying swing of the feeder arm 25 to accord with selected printing positions, the nature of the stock employed and the speed of the press. In Fig. 8, the dotted line 25^a shows the feeder arm 25 in foremost sheet delivering position. If this or another position at the rear thereof is desired for the releasing point of sheets, the arm 65 is fixed so that the cam 66 thereon will swing the lever *d* and cause the latching of the arm 54 by the bar 59 at the selected position. In other words, the arm 65 is set so that the lower valve 38 will seat at the selected position of the feeder arm 25 for the releasing of sheets. This initial or rough adjustment, obtained by setting the arm 65, is made while the feeder is at rest, the finer, second adjustment being made after the feeder is put into operation. This second adjustment consists in turning the screw 55 in or out and thereby varying the unseating of the upper valve 50 with respect to the seating of the lower valve 38, the effect of which can be observed as the sheets are being fed.

A piston 71 in the bore of the standard 10 closes said bore beneath the point of connection therewith of the suction tube 31. This piston renders inoperative the self-tripping throw-off mechanism of the press, when a sheet is grasped by the grip 28.

Changes in the specific form of our invention, as herein disclosed, may be made within the scope of what is claimed without departing from the spirit of our invention.

Having described our invention, what we claim as new and desire to protect by Letters Patent is:

1. The combination with a printing press, of a hollow suction standard mounted on said press, a bearing, a housing on the bearing communicating with said standard and securing said bearing thereon, a rock-shaft

mounted in the bearing, a feeder arm on said rock-shaft, a pneumatic grip carried by the arm from sheet receiving through discharging positions and back, a conduit bringing the grip into communication with the housing, said conduit, housing and standard constituting a suction passageway to the grip, valve mechanism in said housing including two self-closing valve members, one adapted to obstruct and clear the passageway in the standard and the other adapted to admit and bar entrance of air to the housing, a lever, means associated with said lever for opening and permitting the closing of said first valve member, means also associated with said lever for opening and permitting the closing of said second valve member, said latter means being adjustable to vary the opening of said second valve member, the opening of said valve members being alternately accomplished upon reverse swings of said lever, an adjustable cam operated by the rock-shaft for engaging and swinging said lever to permit the closing of the first valve member and to cause the opening of the second valve member at various sheet discharging positions of the grip, a spring anchored to the bearing for retracting said lever, a latch mounted on the bearing to secure the lever against retraction by said spring and means for tripping said latch to cause the opening of the first valve member and the closing of the second valve member at sheet receiving position of the grip.

2. The combination with a printing press, of a bearing, a rock-shaft mounted in the bearing, a feeder arm on said rock-shaft, a pneumatic grip carried back and forth by the arm between sheet receiving and discharging positions, a suction conduit communicating with said grip, valve mechanism incorporated in said conduit and including two self-closing valve members, one adapted to obstruct and clear the conduit and the second adapted to admit and bar entrance of air thereto at a point between the first valve member and grip, a lever, means associated with said lever for opening and permitting the closing of said first valve member, means also associated with said lever for opening and permitting the closing of said second valve member, the opening of said valve members being alternately accomplished upon reverse swings of said lever, an arm on the rock-shaft for engaging and swinging said lever to permit the closing of the first valve member and to cause the opening of the second valve member at sheet discharging position of the grip, a spring for retracting said lever, a latch to secure the lever against retraction by said spring and means for tripping said latch to free said lever, whereby the first valve member is opened and the second

valve member is permitted to close at sheet receiving position of the grip.

3. In a sheet feeding device, a pneumatic grip, means for carrying the same back and forth between sheet receiving and discharging positions, a suction conduit communicating with the grip, valve mechanism incorporated in said conduit and including two yieldingly seated ball valve members, one adapted to obstruct and clear the conduit and the second adapted to admit and bar entrance of air thereto at a point between said first valve member and grip, a lever, means actuated by said lever for unseating and permitting the seating of said first valve member, means also actuated by said lever for unseating and permitting the seating of said second valve member, means, timed to accord with the movement of the grip, for engaging and swinging said lever, in one direction, to permit the seating of the first valve member and to unseat the second valve member at sheet discharging position of the grip, and means for returning said lever to starting position to unseat the first valve member and permit the seating of the second valve member at sheet receiving position of the grip.

4. In a device of the class described, the combination with suction producing means, of a pneumatic grip, means to carry said grip from sheet receiving through various sheet discharging positions and back, a conduit affording communication between said suction producing means and grip said conduit including an enlarged pressure reduction chamber, a valve member for obstructing the conduit between the chamber and grip to cut off suction in the grip, during the latter part of its sheet carrying throw, and to confine the reduction of pressure to the chamber during the return of the grip to sheet receiving position, said valve member being adapted to clear the conduit at said latter position, and a second valve for admitting air to the conduit between the first valve member and grip at said latter part of said throw of the grip and for interrupting the admission of air to said conduit at sheet receiving position of said grip.

5. In a sheet feeding device, a pneumatic grip movable between sheet receiving and discharging positions, a suction conduit communicating with said grip, a valve member for obstructing and clearing said conduit, a second valve member for opening

and closing said conduit to the atmosphere at a point between the grip and said first valve member, an actuating element, means associated with said element for operating said first valve member, means also associated with said element for operating said second valve member, said last mentioned means being adjustable to vary the operation of said second valve member with respect to the first valve member and means for operating said actuating element, said means being adjustable to operate said element at various positions of said grip.

6. In a device of the class described, a movable suction grip, a suction conduit communicating with said grip, adjustable means for obstructing said conduit to cut off suction alterably from the grip, adjustable means for admitting air to the conduit at a point between the obstruction and said grip, said second adjustable means being capable of alterable timing with respect to said first mentioned means to variably supplement the variable sheet freeing effect thereof.

7. In a sheet feeding device, a pneumatic grip movable between sheet receiving and discharging positions, a suction conduit communicating with said grip, a valve mechanism for obstructing and clearing said conduit, a second valve mechanism for opening and closing said conduit to the atmosphere at a point between the grip and said first valve mechanism, an actuator lever common to the two mechanisms and means for swinging said lever, said means being adjustable to operate the lever at different positions of said grip.

8. In a device of the class described, a pneumatic grip, means for moving said grip from sheet receiving position through sheet discharging positions and back, a suction conduit communicating with said grip, a valve in the conduit for obstructing and clearing the same, adjustable means for actuating said valve said conduit having a duct open to the atmosphere at a point between said valve and grip, a second valve for obstructing and clearing said duct and adjustable means independent of said first adjustable means for actuating said second valve.

In testimony whereof, we have signed our names to this specification.
